[57] ABSTRACT

An electrically heated steam and vacuum hand iron. A vacuum port is provided at the periphery of the soleplate of the iron and outwardly of the steam discharge apertures in the soleplate to extract steam and moisture from the pressed fabric, more quickly to dry the pressed fabric, thereby to speed hand ironing operations.

FIG. 6

FIG. 7

FIG. 8

FIG. 9

FIG. 12

102. FIG. 10

FIG. 11

HAND IRON

This invention relates to an improved heated hand iron, and, more particularly, to an electrically heated hand iron for simultaneously heating, steaming and vacuuming fabrics and garments to be pressed.

A wide variety of heated hand irons is presently available. Normally such heated hand irons define steam discharge apertures through which steam is discharged outwardly into a garment to be pressed. Those irons which are generally available for use in the home normally generate steam internally, which steam is then discharged through the soleplate to steam and dampen the material to be pressed. Frequently commercial hand irons utilize steam which is produced in an independent steam generator. With that type of heated hand iron, steam is normally conducted to, thence through the body of the soleplate of the iron to steam discharge apertures in the soleplate. Such heated hand irons normally employ electric resistance heaters for heating the soleplate of the irons themselves.

Although those irons which are presently available adequately steam and moisten fabrics and garments to be pressed, it is not until the moisture is subsequently extracted or removed from the garment or fabric that the garment or fabric is fully ready for hanging on hangers, or for use, etc. As such, the speed and effectiveness of hand-pressing operations, as in commercial establishments, such as dry cleaning establishments, is dependent, at least in part, upon the drying of steamed garments and fabrics.

In accordance with this invention, means for drying steamed garments and fabrics, and for extracting moisture therefrom, simultaneously, or substantially simultaneously, with a hand ironing operation, are provided. To that end, an electrically heated hand iron, such as a steam iron, is provided with a vacuum port means at the peripheral edge of the soleplate, and outwardly or outboard of the steam discharge apertures provided by the soleplate. The port means is in communication with a vacuum conduit which is adapted to be joined to a source of vacuum. As such, vacuum may be continuously drawn through the port means. As soon as the soleplate of the iron has steamed and pressed a portion of a garment or fabric, and as it moves, the port passes over the moistened portion where it draws a vacuum to remove the last traces of the injected moisture.

It has been found that a heated hand iron incorporating such a vacuum system, and particularly a steam iron, will speed a steam hand ironing operation, hence will improve the final finish imparted to garments and fabrics to be pressed. Indeed, a hand iron of this invention may be used, for example, on a garment hung on a hanger, and remote from an ironing board, to steam and dry, or to steam and finish the garment or fabric.

Further objects, advantages, and features of this invention will become apparent from the following description and drawings, of which:

FIG. 1 is a side elevational view, partially broken away, of a heated hand iron of this invention;

FIG. 2 is a rear elevational view, partially broken away, of the iron of FIG. 1;

FIG. 3 is a bottom view of the iron of FIG. 1;

FIG. 4 is an enlarged fragmentary view of FIG. 2;

FIG. 5 is a plan view, partially broken away, of the soleplate of the iron of FIG. 1;

FIGS. 6 and 7 illustrate a further embodiment of a heated hand iron of this invention;

FIG. 8 is a bottom view of a soleplate of yet another heated hand iron of this invention;

FIGS. 9 to 11 are cross-sectional views of FIG. 8, taken along the lines indicated in FIG. 8; and

FIG. 12 illustrates yet another heated hand iron of this invention.

Referring now to the embodiment of FIGS. 1 to 5, inclusive, a steam and vacuum, heated hand iron 10 is seen to include a soleplate 12 and a handle 14. The soleplate provides an expansive flat ironing surface 32, has a wide rear end and gradually tapers to a point at its forward tip edge (see FIG. 3). Soleplate 12 is heated by an electrical resistance heating element 16 of a conventional type, which element is under the control of a temperature switch 26. The heating element 16 is held flat and in firm engagement with the soleplate 12 by a holdown clamp 18. Clamp 18 also securely and firmly holds a vacuum hood 20 in place.

Hold-down clamp 18, vacuum hood 20, and heating element 16 are maintained in the respective positions illustrated in FIG. 1 by a series of nuts 21 which are threaded on a pair of studs (see studs 86 in FIG. 6), secured at the upper surface of soleplate 12. The clamp 18 is covered by a cover 22, which in turn is held in position, as by acorn nuts 24, also threaded on the studs. Handle 14 is mounted on a pair of brackets 28, the lower ends of which are also suitably secured to the studs, as illustrated in FIG. 1.

Soleplate 12 itself may be constructed generally in accordance with U.S. Pat. No. 2,285,757. To that end, a desired pattern of steam discharge apertures 30 open downwardly and outwardly in the flat ironing surface 32 of soleplate 12 (see FIGS. 3 and 5). Steam discharge apertures 30 open inwardly in a steam discharge chamber 34. Chamber 34 is supplied with steam from a source of steam connected to steam inlet 35. Steam passes inwardly through inlet 35, to which a suitable fitting 40 and steam hose may be connected, and through a series of internal passages, such as expansion chambers 36, which are connected in series by connecting passages 38, thence into discharge chamber 34. Because soleplate 12 is heated by heating element 16, any entrained moisture will be converted into steam, so that only dry steam will be discharged through apertures 30.

Heating element 16 is provided with current through a source of electrical power, such as cord 42. The conductors of cord 42 are suitably connected to terminals 44 of heating element 16, through temperature control switch 26.

Steam is intermittently supplied to steam inlet 35 through fitting 40, and generally in accordance with the teachings of U.S. Pat. No. 2,285,757. Desirably, the steam is generated at a remote location, and is allowed to enter inlet 35 in response to operation of a steam switch 46. Steam switch 46 is adapted electrically to signal a remote solenoid-operated valve when steam is desired, thereby to permit steam from the steam generator to pass through a steam hose (not shown) to fitting 40.

Although steam is provided upon demand only, in the embodiment of FIG. 1 suction is provided continuously. However, vacuum may also be under the control of a switch for intermittent operation.

As illustrated in the drawings, vacuum hood 20 overlies and sealingly surrounds and circumscribes the soleplate 12. That is to say, that the hood 20 and soleplate 12 define a channel means or port 50 completely circumscribing the soleplate, which port is defined by the peripheral edge of the soleplate and the inner surface of the vacuum hood 20. The hood is closely adjacent the peripheral edge of the soleplate. As best seen in FIGS. 2 and 4, the port 50 is positioned outwardly or outboard of the steam discharge apertures 30, and opens downwardly, so that as the iron is moved sideways, for example, the steam which was discharged into the underlying fabric or garment, and which was converted into moisture, will be subjected to vacuum and suction to remove the excess moisture, thereby to complete the steam ironing operation. The port 50 is in communication with a vacuum conduit 52, which in turn is adapted to be joined to a vacuum hose or the like which is directly connected to a source of suction.

In the embodiment of FIGS. 1 to 5, the channel or port 50 is continuous and indeed extends around the entire periphery of the soleplate. Preferably, however, it changes in cross-section from rear to front to provide more uniform suction force at all locations. Further, as best seen in FIG. 4, the peripheral edge 54 of hood 20 ends slightly above surface 32 to facilitate the use of the iron 10.

A further iron having a soleplate 60 is illustrated in FIGS. 6 and 7. Soleplate 60 provides an upper surface 62 and a lower flat ironing surface 64. At the forward end of lower ironing surface 64, a plurality of steam discharge apertures 66 are provided. These may be supplied with steam through an internal steam passage 68 and a steam tube 70. Steam tube 70 is suitably joined to a steam generator (not shown).

In the embodiment of FIGS. 6 and 7, a vacuum channel or port comprises a plurality of spaced vacuum openings 72, 74 in the flat lower ironing surface 64. Openings 72 are positioned outboard of the steam discharge apertures 66, and are positioned at one side edge of the soleplate, whereas openings 74 are positioned at the other side edge of the soleplate. Openings 72, 74 are in communication with vacuum passages 76, 78, respectively. Each of the passages, 76, 78, it will be seen in FIG. 6, is wide at the rear of the soleplate and is narrower at the front of the soleplate, the purpose of which is to balance the suction forces along the side edges, thereby to maintain, as closely as possible, a generally uniform suction force from the rear to the tip edge of the soleplate. Each of the port passages 76, 78 is independently and separately in communication with a vacuum conduit 80, 82, although at the remote outer ends, conduits 80, 82 may be joined together and to a suitable common vacuum hose 84 or the like.

The embodiment of FIGS. 6 and 7 provides two port sections, hence two independent peripheral suction zones, one at each side and each adjacent the periphery of the soleplate, thereby to enhance the suction effect created.

Studs 86 may be utilized to mount and secure an electric heating element 16, a clamp 18, and a suitable cover, as well as a handle 14, all generally in accordance with the description of FIGS. 1 to 5.

Referring now to FIGS. 8 to 11, a further iron having a soleplate 100 is seen to comprise an upper surface 102 and a lower flat ironing surface 104. Soleplate 100

may be similar to that of FIG. 6, and is similarly mounted in an iron having a handle 14, a heating element 16, a hold-down clamp 18, and a suitable cover.

Soleplate 100 defines a steam chamber 106 communicating with a series of steam discharge apertures 108. Steam is supplied through steam passage 109. A first suction zone, generally V-shaped at the tip of the soleplate, is defined by a first port section 110, which is in communication with a suction source through a vacuum passage 112, a suction tube 114 and a suction conduit 116. Port section 110 is positioned at the periphery of the soleplate and outboard of apertures 108.

A second port section 120, which is generally U-shaped, extends peripherally around the sides and rear edge of the iron. This port is in communication with suction tube 122, which is also connected to suction conduit 116.

It will be seen that the continuous channels or ports 110, 120 function similarly to the discontinuous ports comprising the series of openings 72, 74 of FIGS. 6 and 7. However, in the embodiment of FIG. 8 a pair of suction zones, one forward and one rearward, are provided.

Referring now to FIG. 12, yet another embodiment of an iron of this invention is illustrated. Soleplate 130, thereof, having a bottom flat ironing surface 132, defines a steam chamber 134 and a series of steam discharge apertures 136. Apertures 136 are supplied with steam through a steam passage 138. A triangular continuous suction port 140 circumscribing the apertures 136 is provided in the forward half or forward portion of the soleplate. A suction source is suitably connected to a suction passage 142.

In the embodiment of FIG. 12, port legs 144 are located at the side edges or periphery of the soleplate, and a further port element 146 joins the legs rearwardly of the steam apertures 136. Thus, as the iron incorporating soleplate 130 is used, no matter how the iron is moved, excess moisture is removed, and, for example, much closer to the steam apertures than in the embodiment of FIG. 8 where a rear port element is at the very back of the iron.

While this invention is susceptible of embodiment in many different forms, there has been shown and described in detail preferred embodiments of the invention. It is to be understood that the present disclosure is intended as an exemplification of the principles of the invention, and is not intended to limit the invention to the embodiments illustrated. The scope of the invention will be pointed out in the appended claims.

What is claimed is:

1. A heated hand iron having a handle and a soleplate providing an expansive flat ironing surface, means for heating said soleplate to an elevated temperature, port means along the peripheral edge of said soleplate and opening downwardly adjacent said ironing surface, said port means comprising a plurality of spaced openings in said flat ironing surface adjacent the peripheral edge of said soleplate, and a vacuum conduit, said conduit being in communication with said port means and being adapted to be joined to a source of vacuum, whereby vacuum may be drawn through said port means when said hand iron is in use, and wherein said soleplate has a wide rear end and

gradually tapers to a point at its forward edge and defines a plurality of steam discharge apertures opening downwardly into said ironing surface and communicating with internal steam passages for transmitting steam to said apertures, said port means being positioned outwardly of said apertures.

2. A heated hand iron having a handle and a soleplate providing an expansive flat ironing surface, means for heating said soleplate to an elevated temperature, port means along the peripheral edge of said soleplate and opening downwardly adjacent said ironing surface, and a vacuum conduit, said port means defining at least two independent port sections, each separately in communication with said vacuum conduit, whereby independent peripheral vacuum zones are provided, said conduit being in communication with said port means and being adapted to be joined to a source of vacuum, whereby vacuum may be drawn through said port means when said hand iron is in use, and wherein said soleplate has a wide rear end and gradually tapers to a point at its forward edge and defines a plurality of steam discharge apertures opening downwardly into said ironing surface and communicating with internal steam passages for transmitting steam to said apertures, said port means being positioned outwardly of said apertures.

3. A heated hand iron having a handle and a soleplate providing an expansive flat ironing surface, means for heating said soleplate to an elevated temperature, port means along the peripheral edge of said soleplate and opening downwardly adjacent said ironing surface, and a vacuum conduit, said conduit being in communication with said port means and being

adapted to be joined to a source of vacuum and wherein said soleplate defines said port means, and further defines vacuum passage means in communication with said port and with said vacuum conduit, whereby vacuum may be drawn through said port means when said hand iron is in use, and wherein said soleplate has a wide rear end and gradually tapers to a point at its forward edge and defines a plurality of steam discharge apertures opening downwardly into said ironing surface and communicating with internal steam passages for transmitting steam to said apertures, said port means being positioned outwardly of said apertures.

4. A heated hand iron having a handle and a soleplate providing an expansive flat ironing surface, means for heating said soleplate to an elevated temperature, port means along the peripheral edge of said soleplate and opening downwardly adjacent said ironing surface, and a vacuum conduit, said conduit being in communication with said port means and being adapted to be joined to a source of vacuum, whereby vacuum may be drawn through said port means when said hand iron is in use, and wherein said soleplate has a wide rear end and gradually tapers to a point at its forward edge and defines a plurality of steam discharge apertures opening downwardly into said ironing surface and communicating with internal steam passages for transmitting steam to said apertures, said port means being positioned outwardly of said apertures, said port means being generally triangular in shape and substantially circumscribing said steam discharge apertures, and being entirely positioned in the forward portion of the soleplate.
